UNITED STATES PATENT OFFICE.

EDWIN H. BROWN, OF MILWAUKEE, WISCONSIN, ASSIGNOR TO ALLI-CHALMERS MANUFACTURING COMPANY, OF MILWAUKEE, WISCONSIN, A CORPORATION OF DELAWARE.

HYDRAULIC TURBINE.

Application filed October 22, 1917. Serial No. 198,535.

This invention relates to improvements in the construction and operation of turbines and has particular relation to improvements in draft tubes for hydraulic turbines.

5 An object of the invention is to provide a turbine draft tube which is simple and compact in construction and efficient in operation.

10 Another object is to provide a draft tube especially applicable to vertical turbines, which is of minimum vertical and horizontal dimensions or extent.

15 A further object is to provide a compact draft tube which will gradually simultaneously change the direction of and decelerate the flow of the water discharged from a turbine rotor.

20 Still another object is to provide a draft tube which will increase to a maximum, the efficiency of the turbine cooperating therewith.

25 It has heretofore been proposed to construct a draft tube of a vertical downwardly flaring conoidal casing cooperating with a flat base plate below the casing, the water being delivered from the casing upon the plate and the flow being gradually entirely decelerated during such delivery. The water after striking the base plate of this prior 30 device, is delivered radially outwardly in all directions and into a chamber either at the edge of or below the base plate, from which chamber it is discharged through a conduit extending in a generally radial direction 35 relatively to the turbine axis.

One objection to this prior art device is that considerable width of foundation space is necessary in order to form a conduit of sufficient capacity to collect the fluid delivered from the edge of the base plate. This 40 excessive width is a factor of considerable importance especially where there are a number of units arranged laterally of each other, since the power house floor space is thereby 45 undesirably enlarged and the cost of the foundation structure is increased.

The present invention contemplates the provision of means for substantially reducing both the vertical and the lateral extent of 50 installations of this type, thereby reducing to a minimum the cost and difficulties of construction but maintaining maximum efficiency of the power units. While the inven-

tion has been disclosed as applied specifically to hydraulic turbines of the vertical shaft open inlet flume type, it may be applicable to other types of turbines. The invention, however, has its greatest utility when applied to axial discharge high speed runners, that is, runners in which the vanes extend as near to the shaft axis as possible. By axial discharge is meant discharge flow in a generally axial direction and this designation is intended to include discharges in which components of the discharge are transverse relatively to the rotor axis.

55 A clear conception of several embodiments of the invention may be had by referring to the drawing accompanying and forming a part of this specification in which like reference characters designate the same or similar parts in the various views.

60 Fig. 1 is a diagrammatic central vertical section through a vertical shaft hydraulic turbine of the open flume type, having a spiral draft tube associated therewith.

65 Fig. 2 is a transverse section through the spiral draft tube, the section being taken along the line II—II—II of Fig. 1 looking downwardly.

70 Fig. 3 is a diagrammatic central vertical section through a vertical shaft open flume hydraulic turbine showing a draft device having adjustable guide vanes therein.

75 Fig. 4 is a diagrammatic transverse central vertical section through another form of draft tube.

80 Fig. 5 is a transverse section through the form of draft tube shown in Fig. 4, the section being taken along the line V—V of Fig. 4 looking downwardly.

85 Fig. 6 is a diagrammatic central vertical section through a vertical shaft open flume hydraulic turbine showing a draft device having stationary guide vanes therein.

90 Fig. 7 is a diagrammatic central vertical section through a vertical shaft open flume hydraulic turbine of a flow type in which the flow adjacent to the inlet and discharge edges of the rotor vanes is axial, the turbine having a vane free draft device associated therewith.

95 Fig. 8 is a diagrammatic central vertical section through a vertical shaft open flume hydraulic turbine of a flow type in which the flow adjacent to the inlet and discharge 100

105

edges of the rotor vanes is axial, the installation having a draft device provided with adjustable guide vanes therein.

Fig. 9 is a diagrammatic central vertical section through a vertical shaft open flume hydraulic turbine of a flow type in which the flow adjacent to the inlet and discharge edges of the rotor vanes is axial, the installation having a draft device provided with stationary guide vanes therein.

Fig. 10 is a diagrammatic transverse central vertical section through another form of draft tube.

Fig. 11 is a transverse section through the form of draft tube shown in Fig. 10, the section being taken along the line XI—XI of Fig. 10 looking in a downward direction.

Referring specifically to Figs. 1, 3 and 6, the hydraulic turbine therein disclosed comprises a high speed rotor 1 consisting of a series of vanes secured to the vertical main shaft 2 and extending inwardly as near to the shaft axis as possible. The turbine vanes extend outwardly in a generally radial direction and may be provided with a rim secured to their outer extremities. The hydraulic turbine disclosed in Figs. 7, 8 and 9, is likewise of the high speed type, but differs from the turbine shown in Figs. 1, 3 and 6, in that the rotor 18 is of the purely axial flow type, wherein the flow of fluid directly adjacent to both the leading and trailing rotor vane edges, is axial.

The turbine receives its supply of water from an open inlet flume 4 past a series of adjustable guide vanes 3 of the usual form. The guide vanes 3 deliver the water inwardly toward the turbine axis with a whirling motion. The guide vanes 3 are preferably arranged with their axes of swing extending longitudinally of the shaft 2, and are adjustably mounted in the stationary turbine casing. The inner portion 14 of the upper wall of the inlet casing is formed downwardly converging or substantially frusto conical, as illustrated in Figs. 1, 3, 6, 7, 8 and 9. The converging wall portion 14 serves as means for guiding the inwardly advancing whirling streams delivered past the guide vanes 3 into the transition space located in advance of the impeller or runner, and changes the direction of advancement of the whirling mass of water passing through the transition space, from a direction perpendicular to the turbine axis to a direction along this axis. The degree of change in direction of flow of the whirling stream is dependent upon the curvature and the length of the guiding surface of the upper wall portion 14 measured in radial planes. In all cases the inlet flow into the rotor chamber is inwardly past the guide vanes 3 with a whirl and may be either inward or axial, directly adjacent the inlet edges of the rotor vanes, depending upon the selected form of

these vanes. The inlet guide vanes 3 and the upper wall portion 14 co-operate to produce a flow having spiral helical stream lines and of increasing velocity approaching the rotor 1.

The discharge flow from the turbine rotor 1 is preferably directed substantially axially directly adjacent the discharge edges of the rotor vanes and may be either forward or rearward relatively to radial planes passing through the turbine axis, or in the direction of these planes. While the latter condition of flow is the one ordinarily sought, such condition is rarely attainable in commercial installations and in high speed turbines the water discharged from the rotor retains considerable velocity of whirl in the same direction as the rotation of the rotor 1. The direction of the discharge flow is changed from the axial direction directly adjacent the rotor 1, to a direction away from the axis and in a plane substantially perpendicular to the turbine axis immediately after leaving the trailing vane edges, by means of an annular outwardly directed conduit 6 surrounding the conoidal core 5. The general direction of the discharge flow through the conduit 6 is indicated by the hyperbolæ α shown in Fig. 1. As illustrated, the annular conduit 6 has its axis of annularity coincident with and hence is symmetrical relatively to the axis of the turbine, the conduit 6 extending from the discharge edges of the runner vanes to points in proximity to an annular surface such as would be formed by revolving about the turbine axis an inclined line III—III shown in Figs. 1 and 7. The upper portion of the symmetrical conoidal core 5 which is surrounded by the annular conduit 6, provides a bearing for the lower portion of the main shaft 2. The conduit 6 is preferably so constructed that in addition to directing the discharge flow outwardly it will initially decelerate this flow, but will not entirely decelerate the same. This formation of the conduit 6 is not, however, essential, and conditions may be such that a deceleration of the flow in the conduit 6 is not desirable. The walls of the passage extending from the discharge ends of the inlet guide vanes 3 to the discharge end of the annular conduit 6, cooperate with the rotor bounding walls to form an annular conduit continuously curving in one direction, that is, having all portions thereof convexly curved with respect to the turbine axis.

The discharge end of the annular diffusing conduit 6 communicates directly with the annular inlet of the spiral chamber 7 at or near the annular surface defined by revolving the line III—III about the turbine axis. The tangentially directed discharge end of the spiral conduit or chamber 7 communicates with a discharge conduit 8 lead-

ing to the tail-race, see Fig. 2. The successive conduits 6, 7 and 8 are in open communication and form a continuous passageway for conducting the water from the turbine.

5 The spiral chamber 7 is formed of increasing cross sectional area advancing around the spiral, and is so proportioned that it will gradually, that is, without abrupt change, further decelerate the flow of water 10 delivered thereinto from the conduit 6. The deceleration of flow in the chamber 7 is preferably carried to such an extent that the water delivered into the conduit 8 will retain sufficient velocity only to produce a 15 flow into the tailrace. As disclosed, the final deceleration of the flow is accomplished in the conduit 8, but this may also in some instances be accomplished in the spiral chamber 7.

20 In the structure disclosed in Figs. 3 and 8, adjustable guide vanes 9 are provided within the conduit 6 for the purpose of either changing the direction of the discharge flow from forward to rearward relatively to the direction of rotation of the 25 rotor 1, or for merely slightly varying this direction of flow. These guide vanes 9 may be of ordinary form and may be made adjustable by providing pivots at their opposite ends and shortening the vanes 9 sufficiently to produce the necessary clearance adjacent the pivots between the ends of the vanes 9 and the torous shaped surfaces of the conduit 6, to permit the desired adjustment.

30 The guide vanes in the discharge passage may also be made stationary as illustrated in Figs. 6 and 9. These stationary guide vanes 19 are formed to produce the desired direction of flow of the water into the spiral chamber 7. The stationary guide vanes 19 also cooperate with the guide vanes 3 to provide mechanical supports for the upper and lower turbine casing portions.

35 Referring specifically to Figs. 4 and 5, the tailrace arrangement shown therein comprises a casing 10 having a conoidal core 11 formed concentrically relatively to the turbine axis, and forming a spiral chamber 12 surrounding the conoidal core 11. The spiral chamber 12 is of somewhat different form than the chamber 7 of the device disclosed in Figs. 1 and 2, and communicates with a discharge conduit 13 of lower vertical height than the conduit 8 of the preceding disclosure. The spiral chamber 12 is again formed to produce substantially complete deceleration of the discharge flow as in the preceding case, the conduit 13 performing only a slight final deceleration.

40 It will be noted that by arranging the draft tube as a spiral surrounding the turbine axis, efficient deceleration of the flow may be produced and the over-all height of the draft tube is reduced to a minimum,

thereby eliminating necessity of providing expensive foundation substructure, such as has been necessary in similar installations of the prior art. The spiral formation of draft tube, furthermore, permits gradual 70 deceleration of the flow in a relatively long conduit 7, the lateral extent of the collecting conduit 7 being reduced to a minimum by winding the decelerating chamber around the turbine axis as near to the rotor 75 1 as possible. This construction eliminates the objectionable spreading out of the prior art construction referred to hereinabove, since in that construction considerable width is necessary in order to completely 80 decelerate the flow in the desirably short vertical distance. The turbines with spiral draft tubes may therefore be placed closer together, thereby reducing the necessary floor space to a minimum. 85

90 The spiral chamber 7, 12 will in each case be formed of the proper direction of spirality to correspond with the direction of rotation of the rotor and with the direction of the discharge flow. The guide vanes 9, 19 may be utilized to change the direction of the discharge flow to conform with the hand of spiral employed and may also be utilized to produce more efficient guiding of the flow into the collecting chamber. With 95 the form of draft tube disclosed in Figs. 4 and 5, the vertical height may be reduced still more than in the form disclosed in the other figures due to the widening of the discharge conduit 13, thereby making the 100 cross-section of this conduit rectangular or elliptical rather than circular as in Fig. 1.

105 It should be understood that it is not desired to be limited to the exact details of construction herein shown and described, for obvious modifications within the scope of the appended claims may occur to a person skilled in the art.

110 It is claimed and desired to secure by Letters Patent:

1. In combination, a turbine having an inwardly directed inlet and an axially directed discharge, guide vanes for controlling the inlet to said turbine, means for directing the inward inlet flow along the turbine axis, a conduit for outwardly directing the axial discharge flow and for initially decelerating said flow, guide vanes in said conduit, and means forming a spiral collecting chamber communicating with said conduit for further decelerating said flow. 115

2. In combination, a hydraulic turbine having an axially directed discharge, a conduit for outwardly directing the axial discharge flow and for initially decelerating said flow, guide vanes in said conduit, and means forming a spiral collecting chamber communicating with said conduit for further decelerating said flow. 125

3. In combination, a hydraulic turbine 130

- 4
- having a vertical axis and an axially directed discharge, a conduit for horizontally directing the axial discharge flow and for initially decelerating said flow, guide vanes in said conduit, and means forming a spiral collecting chamber communicating with said conduit for further decelerating said flow.
5. In combination, a hydraulic turbine having an axially directed discharge, a conduit for outwardly directing the axial discharge flow and for initially decelerating said flow, adjustable guide vanes in said conduit, and means forming a spiral collecting chamber communicating with said conduit for further decelerating said flow.
6. In combination, a hydraulic turbine comprising an impeller having an axially directed discharge, a conduit for outwardly directing the axial impeller discharge flow and for decelerating said flow, said conduit being formed to conduct the discharge flow in a direction perpendicular to the impeller axis immediately upon leaving the turbine impeller, and means forming a spiral collecting chamber communicating with said conduit.
7. In combination, a hydraulic turbine comprising an impeller having an axially directed discharge, a conduit for outwardly directing the axial impeller discharge flow and for initially decelerating said flow, said conduit being formed to conduct the discharge flow in a direction perpendicular to the impeller axis immediately upon leaving the turbine impeller, guide vanes in said conduit, and means forming a spiral collecting chamber communicating with said conduit for further decelerating said flow.
8. In combination, a hydraulic turbine comprising an impeller associated with an end of a shaft, means forming a velocity reducing spiral conduit surrounding the axis of said shaft for receiving the discharge flow of said impeller, and a bearing for the end of said shaft located in close proximity to and surrounded by said conduit.
9. In combination, a hydraulic turbine comprising an impeller associated with an end of a shaft, means forming a velocity reducing spiral conduit surrounding the axis of said shaft for receiving the discharge flow of said impeller, conduit means between said impeller and said conduit for changing the direction of the impeller discharge flow, and a bearing for the end of said shaft located in close proximity to and surrounded by said conduit means.
10. In combination, a hydraulic turbine comprising an impeller rotatable about an axis, means forming a velocity reducing spiral conduit for receiving the discharge flow from said impeller, and adjustable means between said impeller and said conduit for varying the direction of flow of fluid delivered from said impeller.
11. In a hydraulic machine, a rotor, means forming an annular radial flow inlet conduit at one side of said rotor and extending toward the rotor axis, means forming a spiral discharge conduit at the opposite side of said rotor and extending away from the rotor axis, means cooperating with said rotor to form an annular conduit continuously curving in one direction and connecting said inlet and said discharge conduits and adjustable means within said connecting conduit at the discharge side of said rotor.
12. In a hydraulic machine, a rotor, means forming an inlet conduit shaped to deliver fluid toward the axis of said rotor with a spiral helical stream lines and with increasing velocity, said rotor being formed to receive and to discharge said fluid with axial components, means forming a discharge conduit shaped to deliver said fluid away from said axis with spiral helical stream lines and with decreasing velocity, and means in said discharge conduit for varying the degree of whirl of the fluid passing therethrough.
13. In a hydraulic machine, a rotor formed to receive and to discharge fluid with axial components, a shaft for said rotor, means forming an inlet conduit surrounding the axis of said shaft and curving toward said rotor convergently, means forming a discharge conduit surrounding said shaft and receding from the axis of said rotor, means for varying the degree of whirl of fluid passing through said discharge conduit, and means forming a spiral chamber communicating with said discharge conduit.
14. In a hydraulic machine, a rotor formed to receive and to discharge fluid with axial components, a shaft for said rotor, means forming an annular curved inlet conduit surrounding the axis of said shaft and approaching said rotor convergently, a series of guide vanes in said inlet conduit remote from said rotor, means forming a discharge conduit surrounding the axis of said shaft and receding divergently from said rotor, and a series of guide vanes in said discharge conduit.
15. In a hydraulic machine, means forming an annular inlet passage, means forming an annular discharge passage, a rotor located between said passages and cooperating there-

- with to form an annular conduit continuously curving in one direction, and an annular series of adjustable vanes within said conduit beyond the delivery end of said rotor.
- 5 16. In a hydraulic machine, means forming an annular inlet passage, means forming an annular discharge passage, a rotor located between said passages and cooperating therewith to form an annular conduit continuously curving in one direction, an annular series of adjustable vanes within said conduit beyond the delivery end of said rotor, and means forming a spiral delivery passage communicating with said discharge passage.
- 10 17. In a hydraulic machine, means forming an annular radial flow inlet passage, means forming an annular radial outward flow discharge passage, a rotor located between said passages and cooperating therewith to form an annular conduit continuously curving in one direction, and an annular series of adjustable vanes within said conduit beyond the delivery end of said rotor.
- 15 18. In a hydraulic machine, means forming an annular radial flow inlet passage,
- means forming an annular radial outward flow discharge passage, a rotor located between said passages and cooperating therewith to form an annular conduit continuously curving in one direction, an annular series of adjustable vanes within said conduit beyond the delivery end of said rotor, and means forming a spiral delivery passage communicating with said discharge passage.
- 20 19. In a hydraulic machine, means forming an annular radial flow inlet passage, adjustable means for varying the direction of flow of the fluid entering said passage, means forming an annular radial outward flow discharge passage, a rotor located between said passages and cooperating therewith to form an annular conduit continuously curving in one direction, adjustable vanes within said conduit beyond the delivery end of said rotor, and means forming a spiral flow decelerating delivery passage communicating with said discharge passage.
- 25 In testimony whereof, the signature of the inventor is affixed hereto.
